UNITED STATES PATENT OFFICE

ISAAC C. GRAY, OF LOGANSPORT, INDIANA, ASSIGNOR OF ONE-THIRD TO JESSE O. GILLENTWATER, OF PERU, INDIANA, AND ONE-THIRD TO JACOB E. LUDDERS, OF LOGANSPORT, INDIANA.

WINDOW-SHADE HOLDER AND CURTAIN-POLE SUPPORT.

1,083,010.

Specification of Letters Patent.

Patented Dec. 30, 1913.

Application filed January 9, 1913. Serial No. 741,063.

To all whom it may concern:

Be it known that I, ISAAC C. GRAY, citizen of the United States, residing at Logansport, in the county of Cass and State of Indiana, have invented certain new and useful Improvements in Window-Shade Holders and Curtain-Pole Supports, of which the following is a specification.

This invention relates to window fixtures, 10 and more particularly to a combination shade-holder and curtain pole support.

The primary object of the invention is to provide improved means for securing window shades in position upon a window frame, said means comprising spring controlled bracket members adapting the device for use upon window frames of varying width.

A further object of the invention is to 20 provide improved means for adjusting shade rollers laterally so that the improved fixtures will be adapted for shades of different widths.

A further object of the invention is to 25 provide a curtain pole holder of improved form capable of ready adjustment.

The construction of the several elements of the improvement will be fully described hereinafter in connection with the accompanying drawing which forms a part of this specification, and their novel features will be set forth in the appended claim.

In the drawing: Figure 1 is a front elevation of a portion of window frame equipped 35 with my improvements. Fig. 2 is a horizontal section taken through one of the telescopic brackets employed. Fig. 3 is an end view partly in vertical section showing one embodiment of the device. Fig. 4 is a detail sectional view illustrating one form of spring used in connection with the telescopic brackets.

Referring to Figs. 1, 2 and 3 the reference numerals 1 and 2 designate telescopic 45 bracket members, the inner one 1 of which is provided with a cross bar 4 to which is attached one end of a coil spring 5, the opposite end of which is secured to the adjacent end of the outer bracket member 2. These 50 members 1 and 2 are provided with flanges 6 and 7 (one for each member) which abut against the parallel side bars of the window

frame 8, the function of the spring 5 being to clamp the two bracket members against the sides of the frame as best seen in Fig. 2. 55 The two bracket members are connected by interlocking edge flanges 9 and 10 so that said members are readily adjustable telescopically adapting the bracket members for use upon window frame side bars of 60 different widths.

In connection with the bracket members I employ means for supporting a shade roller. Various forms of devices for this purpose may be resorted to; that shown in Figs. 1 65 and 3 comprising sleeves 11 slidably supported upon the brackets, and provided with projecting arms 12 having bearings 13 to receive the ends of the shade roller. I also utilize the bracket members as supports for 70 longitudinally adjustable curtain poles. In Fig. 1 I show a pole made up of two members 14 and 15 having their ends provided with loops 16 by means of which a telescopic connection of the pole members is 75 effected. The pole members are supported by depending arms 17 held by arms 18 projecting from the outer ends of the bracket members.

Having fully described my invention, 80 what I claim as new and desire to secure by Letters Patent is:—

The combination with a window frame, of shade holders, each comprising trough shaped telescopic sections, each section provided with a flange to engage said frame and one of said sections having a cross bar, a coil spring located within the trough like sections and secured at one end to the cross-bar and at its opposite end to the outer end 85 of the other section, a sleeve slidably supported on one of the telescopic sections and having a projecting arm formed with a bearing, an arm secured to one of said sections for supporting a curtain, and a longitudinally adjustable curtain pole supported 90 by said arms substantially as described.

In testimony whereof I affix my signature in presence of two witnesses.

ISAAC C. GRAY.
